(57) **CLAIM**

The ornamental design for a wind screen, as shown and described.

DESCRIPTION

FIG. 1 is a perspective front view of the wind screen disclosed herein;

FIG. 2 is a top-side view of the wind screen disclosed herein;

FIG. 3 is a front-side view of the wind screen disclosed herein;

FIG. 4 is a bottom-side view of the wind screen disclosed herein;

FIG. 5 is a back-side view of the wind screen disclosed herein;

FIG. 6 is a right-side view of the wind screen disclosed herein, a left-side view (not shown) is a mirror image of this right-side view; and,

FIG. 7 is a left-side view of the wind screen disposed on a cooking apparatus.

The broken lines, shading, and cross-hatching presented in the drawings are for illustration only and do not form a part of the claimed design.

1 Claim, 4 Drawing Sheets
